J. M. Wilson

ATTORNEY

UNITED STATES PATENT OFFICE.

ABRAHAM SUDEROV, OF NEW YORK, N. Y.

METHOD OF MAKING FINGER RINGS.

Application filed September 19, 1925. Serial No. 57,313.

This invention relates to finger rings, and particularly to the process of fabricating the same, as it is possible, with this new method, to accomplish all of the desired results, and 5 produce a ring equal, if not superior, to what has been made in the past, at a greatly reduced expenditure of both time and labor.

One of the features of my invention consists of producing in dies, in one operation 10 each, the two sections of the ring hoop, shaped and formed and provided with any desired design.

It has been the practice heretofore to stamp out rings in one flat piece, and then 15 to bend up the ends to be soldered together; or to stamp out two halves on the line of the flat axis of the ring, which were then soldered together throughout their annular surfaces. The latter course had to be followed because 20 it would have been impossible to remove the ring from the dies, had it been in one piece.

The economy in making my device results 25 from the fact that a workman who could produce four or five rings a day under the old methods can turn out from twenty to twenty-five finished articles, and, in addition, there is a great saving in losses from the filings which is an important item when working in precious metals.

As is obvious, any suitable metal such as 30 gold, white gold, silver, platinum, etc., etc., works equally well, and any suitable design and ornamentation may be employed.

Other advantages and full details will be 35 found in the following specification, and the accompanying drawings, in which:

Fig. 1 is a perspective view of the blank from which one of the two ring sections is formed.

Fig. 2 is a view of one of the ring sections 40 as it comes from the die.

Fig. 3 is a perspective view of the two ring sections placed together before soldering, and held by a binding wire—a portion being broken away to show the under cuts 45 formed in the die.

Fig. 4 is a view of a finished ring, with the top soldered in place.

In the said drawings, the blank 5 is shown 50 with a broad upper section 7, which tapers

downwardly to form the narrower lower section 6.

In Fig. 2 one of the two ring sections is shown as it comes from the die, with a design 55 formed in the upper portion of the hoop.

In Fig. 3 the two sections are shown positioned together ready for soldering, and held against movement by the binding wire 9.

After the soldering operation, the top 10 is mounted in place and the ring appears as in 60 Fig. 4.

The method employed is as follows:—The blank 5 is stamped out in the usual manner; the said blank is then placed in a die and formed in one operation, as shown in Fig. 2; 65 two of these sections are then secured together with a binding wire and soldered where the inner edges meet; the top is then soldered on, the ring is polished, and the article is completed.

As is obvious, practically any design can be utilized and embodied in the dies so that in one operation, one of the flat blanks can be transformed into a formed half section ready for soldering.

I claim:

1. The method of forming finger rings which includes cutting sheet material into units with a blanking die, pressing each of said units into semi-annular configuration 80 with a forming die, then oppositely positioning two of said units with their ends abutting and while so positioned securing the adjacent ends of the units together to form an annulus.

2. The method of forming finger rings which includes cutting sheet material into units with a blanking die, pressing each of said units into semi-annular formation with a forming die, and by means of the same die 85 and at the same time embossing each of said units with an ornamental design, then oppositely positioning two of said units with their ends abutting and while so positioned securing the adjacent ends of the units together 90 to form an annulus.

In testimony whereof I have affixed my signature.

ABRAHAM SUDEROV.
